UNITED STATES PATENT OFFICE.

JOHN HENRY COWAN, OF KANSAS CITY, MISSOURI, ASSIGNEE, BY MESNE ASSIGNMENTS, TO NICHOLSON CONSTRUCTION COMPANY, A CORPORATION.

COMBINATION HAIR CUTTER AND SAFETY RAZOR.

Application filed April 3, 1922. Serial No. 549,072.

To all whom it may concern:

Be it known that I, JOHN H. COWAN, a citizen of the United States, residing at Kansas City, in the county of Jackson and State of Missouri, have invented a new and useful Improvement in Combination Hair Cutters and Safety Razors, of which the following is a specification.

This invention relates to improvements in combination hair cutters and safety razors and will be more particularly described in the following specification.

The invention is illustrated in its preferred embodiment in the accompanying drawings, in which—

Figure 1 is a top plan view of the device; Fig. 2 is a view of the same in side elevation, showing a different mounting of the handle; Fig. 3 is a view taken as indicated by the line 3 of Fig. 1; Fig. 4 is a view taken as indicated by the line 4 of Fig. 1; Fig. 5 is a top plan view of one of the parts of the device; Fig. 6 is a bottom plan view of one of the parts of the device; and Fig. 7 is a top plan view of a blade adapted for use with the device.

In general, the device may be said to comprise a blade-supporting member A, a comb-plate B, a handle C and a blade D. The member A is preferably formed of two parts 10 and 11. 10 indicates a rectangular shaped casting having its bottom face 13 formed in a double curve. The forward edge of this face is indicated by 14 and is sharpened but not sufficiently to form a cutting edge, such sharpened edge or guard edge 14 being formed by the meeting of the curved surface 13 and the flat top surface 15 of the part 10. The ends of the edge 14 project forward a slight distance beyond the edge 14 to form the two projecting guards 16. 11 indicates a rectangular shaped flat plate adapted to be fastened to the part 10; the two parts when thus fastened together making the blade-supporting member. The parts 10 and 11 are held together by means of the screws 17 which extend thru the holes 18 in the part 11 and enter the threaded holes 19 in the part 10.

A shoulder 20 is formed on the part 10 of substantially the thickness of the plate 11 so that when the plates 10 and 11 are fastened together, the upper surface of the plate 11 will be substantially in a plane with the upper surface 15 of the part 10. A longitudinal

groove 21 is provided in the part 10 near its forward edge.

The part 10 is provided with an upwardly extending lug 30 and the part 11 has a somewhat larger downwardly extending lug 31. These lugs are of such a length that when the parts 10 and 11 are fastened together the upper end of the lug 30 will bear against the lug 31. When the parts are thus fastened together the lug 30 serves as a pivot pin for a handle-retaining member 35, such member 35 being provided with a hole adapted to be embraced by the lug 30. The part 10 is also provided with an annular groove 37 surrounding the lug 30 in which lies a spiral spring 38. The purpose of this spring 38 is to hold the pivoted end of the handle-retaining member 35 in frictional engagement with the lug 31 on the part 11 to prevent loose swinging of this handle-retaining member when the same is not in use. By means of this frictional engagement, such handle-retaining member 35 will remain yieldingly in any position in which it is put. It will be seen that by this construction the handle-retaining member 35 may be pivoted on the lug 30 from side to side. In addition to the spring 38, additional spring-retaining means are provided for yieldingly holding this handle-retaining member 35 in either one of its side positions.

Such means comprise small spring-clips 40 which are clamped between the parts 10 and 11 when they are fastened together. Such spring-clips 40 lie within grooves 41 provided in the part 11 and are provided with holes in their ends thru which the screws 17 pass. The free ends of the spring-clips 40 are bent downwardly slightly and then upward in order to form spring catches 42 adapted to engage the swinging end of the handle-retaining member 35 and yieldingly hold it in either one of its side positions.

The handle-retaining member 35 is of such a length that when it is in either of its side positions its end will be substantially flush with the ends of the parts 10 and 11. The end of such handle-retaining member 35 is provided with a threaded hole 50 adapted to receive the threaded end 51 of a handle 52. This handle 52 is provided at the end of the threaded part with a shoulder 53, so that when the part 51 is screwed into the hole 50, such shoulder 53 will bear against the ends of the parts 10 and 11.

A longitudinal

and 11 and serve to hold the handle firmly in position and prevent swinging of the part 35. It is obvious that the part 35 may be swung to either side and the handle 52 thus attached, thus permitting the device to be assembled with a handle on either side for right or left-hand use.

In Fig. 1 the device is shown with the handle in one position in solid lines and with the handle indicated in the other position by the broken lines. The lug 30 is provided with a centrally arranged internally threaded hole 70 and the projection 31 on the part 11 is provided with a hole 71 lying in alignment with the hole 70 and forming a continuation thereof. The part 11 is provided with two upwardly extending lugs 73. The comb-plate B is substantially rectangular in shape and provided at its forward edge with the teeth 75. The rear edge of the comb-plate B is bent downwardly as indicated by 76. Two notches 77 are formed adjacent the rear edge of the comb-plate B in order to afford a grip for the finger 20 nails in adjusting the position of such comb-plate. This comb-plate is provided with two rectangular shaped slots 78 adapted to accommodate the lugs 73. Between the slots 78 arranged parallelly therewith lies a third slot 79.

D indicates a blade adapted for use with the device. It will be noted that this blade has two cutting edges. Near each of the cutting edges the blade D is provided with a pair of holes 90 adapted to accommodate the lugs 73. Between each pair of holes 90 lies a circular hole 91 adapted to register with the hole 71 in the part 11 when the blade D is in place on the blade-supporting member. A thumb-screw 92 is provided for the purpose of clamping the blade D on the blade-supporting member and holding the comb-plate on top of the same. This thumb-screw 92 is provided with a threaded part 93 adapted to bear against the comb-plate B.

In assembling the device, the handle-retaining member 35 is slipped over the pivot lug 30 and the parts 10 and 11 are then permanently fastened together with the screws 17, with the springs 40 in place. These parts 10 and 11, with the handle-retaining member 35 pivoted on the lug 30, remain permanently together, the parts 10 and 11 comprising the blade-supporting member referred to herein by A. In order to prepare the device for use, a blade D, preferably made out of thin sheet metal, is placed in position on the part A, with the lugs 73 extending thru the holes 90. The hole 91 in the blade will then register with the hole 71. The comb-plate B is then placed over the blade, with the lugs 73 projecting thru the slot 78 and the hole 71 registering with the slot 79. This comb-

plate may be adjusted to give the desired length of teeth 75 projecting in front of the cutting edge of the blade, the slots 78 and 79 permitting such adjustment. When the comb-plate is adjusted as desired, the thumb-screw 92 is screwed into the holes 71 and 70 until the shoulder 94 bears up against the comb-plate, pulling it against the part A and clamping the blade and comb-plate firmly in the desired position. When the blade is in place, its cutting edge is substantially in line with the forward points of the guards 16.

The slots 78 in the comb-plate B are made large enough so that the lugs 73 will fit somewhat loosely therein, thus permitting a slanting adjustment of the comb-plate if desired. With such adjustment, the forward ends of the teeth 75 will not lie parallel with the cutting edge of the blade (indicated by 101), but will form an angle therewith. Such an adjustment of the comb-plate is desirable or useful at times in trimming the hair.

When it is desired to use the device as a razor, the comb-plate B is set back. The exact setting of the comb-plate may be made to suit the desire of the user. For ordinary shaving it is usually found best to set the comb-plate B back until the forward ends of the teeth 75 lie slightly in front of the cutting edge 101 of the blade D. By setting the comb-plate back farther than this, the device is adjusted for closer shaving. If desired, the comb-plate B may be set back as far as it will go with the forward ends of the teeth 75 lying slightly back of the cutting edge 101 of the blade D. When in this position the teeth 75 do not function at all, and the device acts in somewhat the same manner as an ordinary razor, except that the forward guard edge 14 of the part 10 prevents too deep cutting of the blade and therefore acts as a safety guard. If desired, the comb-plate B may be entirely removed when the device is to be used for close shaving.

In using the device, the curved surface 13 is placed next to the skin. In Fig. 2 I have indicated by the broken line 103 the skin surface. It will be noted that adjustment of the comb-plate B serves to space the cutting edge of the blade from the skin surface 103. By this adjustment the device may be set to cut the hair any desired length. In Fig. 2, by the broken line, I have shown the comb-plate B set back as far as it will go, for very close shaving, as described above, where it is not desired to have the teeth 75 function at all. When in this position the cutting edge of the blade D is permitted to touch the face for close shaving, the face in such case being indicated by the broken lines 103a. When the device is used for shaving, the tapered guard points 16 act to prevent cutting of the flesh by the corners.

of the blade. These guards 16 are especially useful for protection in shaving concave surfaces, such as within the ears, under the arms, and the like. They also act as guards when the device is being used as a hair cutter with the comb-plate adjusted forward. In such cases, these guard-plates 16 are especially useful in preventing cutting by the corners of the blade, in trimming the hair around the ears, and the like.

The thumb-screw 92 may be removed and the handle C substituted therefor, if desired. When the handle is thus used it serves to clamp and hold the blade and comb-plate in place. The handle is shown in such position in Fig. 2. If desired, however, the thumb-screw 92 may be used for holding the comb-plate and blade in place, and the handle C may then be attached to the handle-retaining member 35 and fastened in position on either side of the device, as explained above, thus making the device adaptable for either right-hand or left-hand use.

In describing the device or speaking of the device, I have referred to the side of the device adjacent to the skin when in use as the bottom and the other side the top; and the forward edge in the cutting movement as front.

While I have shown and described certain embodiments of my invention, it is to be understood that it is capable of many modifications. Changes, therefore, in the construction and arrangement may be made

without departing from the spirit and scope 35 of the invention as disclosed in the appended claims, in which it is my intention to claim all novelty inherent in my invention as broadly as possible in view of the prior art.

I claim:

1. A device of the character set forth, comprising a blade-supporting member having a substantially flat blade-supporting surface on top with a tapered forward guard edge, a handle-retaining member pivotally mounted on said blade-supporting member, a handle detachably secured to said handle-retaining member, a thin safety razor blade adapted to lie on said flat blade-supporting surface with its cutting edge slightly in front of said tapered guard edge, and a comb-plate with teeth on its forward edge adjustably mounted on said blade-supporting member and lying over said blade.

2. A device of the character set forth, comprising a blade-supporting member having a substantially flat blade-supporting surface on top with a tapered forward guard edge, a handle-retaining member pivotally secured to said blade-supporting member and adapted to swing thru an arc of 180°, and a handle adapted to be attached to said handle-retaining member when the same is at either end of its swing, the attachment of said handle to said handle-retaining member also serving to lock the same in position.

JOHN HENRY COWAN.
